Primary Examiner — George D Kirschbaum(74) Attorney, Agent, or Firm — Morgan, Lewis & Bockius LLP; Brett A. Lovejoy(57) CLAIM

An ornamental design for a gaming table, as shown and described.

DESCRIPTION

FIG. 1 is a first perspective view of a first embodiment of our new design of a gaming table;

FIG. 2 is a top view of the design of FIG. 1;

FIG. 3 is a front view of the design of FIG. 1;

FIG. 4 is a left side view of the design of FIG. 1; and,

FIG. 5 is a right side view of the design of FIG. 1.

The broken line showing of legs and corners, and the ends of rails is included for the purpose of illustrating portions of the "article" and forms no part of the claimed design.

1 Claim, 5 Drawing Sheets(56)
